UNITED STATES PATENT OFFICE.

PIERRE PLANTINGA, OF CLEVELAND, OHIO.

OIL SPRAY FOR CARBURETORS.

Application filed October 12, 1921. Serial No. 507,212.

To all whom it may concern:

Be it known that I, PIERRE PLANTINGA, a citizen of the United States, resident of Cleveland, county of Cuyahoga, and State 5 of Ohio, have invented new and useful Improvements in Oil Sprays for Carburetors, of which the following is a specification, the principle of the invention being herein explained and the best mode in which I 10 have contemplated applying that principle, so as to distinguish it from other inventions.

This invention relates to a spraying device which is particularly useful in connection with carburetors and has for its object to provide a spraying device capable of distributing the oil in a rain spray throughout the entire area of the checker brick and so constructed as to be capable 20 of withstanding the high temperatures of the carburetor chamber. A further object of the invention is to provide a spray nozzle that will properly distribute the oil at low pressures as well as at high pressures making it possible to regulate the flow of oil by varying the pressure under 25 which it is supplied to the nozzle, making it unnecessary to provide adjustable flow regulating means in the nozzle.

30 The annexed drawings and the following description set forth in detail certain means embodying my invention, the disclosed means, however, constituting but one of the various mechanical forms in which the 35 principle of the invention may be applied.

In said annexed drawings:

Fig. 1 is a vertical section through the preferred form of spray nozzle.

40 Fig. 2 is an enlarged sectional detail view of the discharge portion of the nozzle shown in Fig. 1.

Fig. 3 is a section on line III—III of Fig. 2.

45 Fig. 4 is a sectional detail view similar to Fig. 2 of a slightly modified form of nozzle.

Fig. 5 is a section on line V—V of Fig. 4.

Fig. 6 is a side elevation of the perforated inner nozzle head.

50 Fig. 7 is a plan view of the head shown in Fig. 6.

Fig. 8 is a side elevation of the perforated washer fitting within the inner nozzle head.

55 Fig. 9 is a top plan view of the washer shown in Fig. 8.

Fig. 10 is a plan view of the retaining ring for the washer.

Fig. 11 is a sectional view of a checker brick carburetor showing the nozzle in side 60 elevation.

Fig. 12 is a vertical section through a modified form of nozzle.

Fig. 13 is a side elevation of the perforated washer disposed in the outer discharge passage of the nozzle shown in Fig. 12.

Fig. 14 is a plan view of the washer shown in Fig. 13.

Fig. 15 is a side elevation of the perforated washer disposed in the inner discharge passage of the nozzle.

Fig. 16 is a plan view of the washer shown in Fig. 15.

Fig. 11 of the drawing shows the portion of the gas generating apparatus to which my invention relates. In said figure is shown the carburetor chamber 1, partially filled with checker bricks, and provided with a gas passage 3 communicating 80 with the gas generator. The top of the carburetor chamber 1 has a central opening 4 communicating with an upwardly extending casing 5 which communicates with the secondary blast conduit 6. Disposed 85 centrally of the casing 5 is the oil spray nozzle 7 which is supplied with oil from an oil pipe 8.

In delivering oil to a carburetor chamber it is desirable that the oil be delivered 90 uniformly to all parts of the checker brick. The usual types of spray nozzles adapted to discharge liquid in a uniform rain spray, however, cannot be used in carburetor chambers for the reason that their construction is such that they are quickly destroyed by the intense heat to which they are subjected. It is necessary that the parts of the nozzle be so constructed as to be free to expand and contract without 95 distortion and without setting up disruptive stresses therein. For this reason the type of spray nozzle which has been most commonly used is one of the single orifice type in which the oil is discharged through 100 an annular converging orifice in the form of a diverging conical stream commonly called an umbrella spray. The nozzle which constitutes the present invention is designed to obtain a very uniform distribution 105 of oil in a rain spray with a nozzle of the umbrella spray producing type.

capable of withstanding the intense heat of the carburetor chamber.

The preferred form of nozzle shown in Fig. 1 comprises protective casing 9 threaded into the top of the casing 5; a tubular body member 10 within the casing 9, having a threaded engagement with an elbow casting 11 bolted to the top of the casing 5 and communicating with the oil supply pipe 8; and a discharge head which will be herein-after described.

The nozzle discharge head comprises an outer casting 12 screwed upon the lower end of the body member, an inner nozzle head 13 secured within the casting 12, and a washer member 14 secured within the inner head 13. The inner nozzle head 13 has a peripheral flange 15 fitting within the upper portion of the casting 12 and resting on an internal shoulder 16 therein. The flange 15 is of slightly greater diameter than the threaded lower end of the tubular body member 10 and is clamped between the shoulder 16 and the end of the tubular member 6 when the casting 12 is screwed onto said member. The inner head 13 has an internal shoulder 17 adapted to receive the peripheral flange 18 of the inner washer 14. The flange 18 is retained against the shoulder 17 by means of split retaining ring 19 fitting in a peripheral groove inside the head 13. The casting 12 has a converging conical inner surface 20 below the shoulder 16 terminating in a restricted central passage 21 and a short conical discharge portion flaring outwardly from the passage 21. The inner nozzle head 13 has a converging conical outer surface 23 below the flange 15 which is concentric with the conical inner surface 20 of the casting 12 when secured therein. The surfaces 20 and 23 form between them an annular outer discharge orifice 24. The inner surface of the inner nozzle head 13 terminates below the internal shoulder 17 in a converging conical portion 25 similar to the inner surface 20 of the outer casting. The conical portion 25 terminates in a central flared aperture 26. The inner washer 14 has a depending stem with a conical pointed end 27. When the washer 14 is secured within the inner nozzle head the conical point 27 is concentric with the inner conical surface 25 of the inner nozzle head 13 and forms therewith an inner annular discharge orifice 28. The peripheral flange 15 of the inner head 13 is provided with a series of passages 29 all slanting in the same direction with respect to axial planes. The passage of the oil through the slanting passages 29 imparts a whirling motion thereto. The peripheral flange 18 of the inner washer 14 has similar slanting passages 30 preferably slanting in a direction opposite to that of the passage 29 (as clearly shown in Fig. 3) for imparting a whirling

motion to the oil in passing through the inner annular orifice 28.

As indicated in Fig. 2 an umbrella spray indicated by dotted lines 31 in said figure is discharged from the outer annular orifice 24. A second umbrella spray indicated by the dotted lines 32 is discharged from the inner annular orifice 28. The interference of the two concentric sprays whirling in opposite directions breaks up the two whirling annular sprays into a rain spray which delivers oil quite uniformly to all parts of the checker brick.

The passages 29 and 30 may be arranged to slant in the same direction as shown in Figs. 4 and 5. While the result produced in this case is greatly superior to a single umbrella spray the interference between the two sprays is not as great as where the sprays have a whirling motion in opposite directions and the distribution of oil is not as uniform.

In the nozzles heretofore used for discharging umbrella sprays, it has been necessary to maintain an oil pressure of from 35 to 40 lbs. in order to provide an efficient spray. I have found that the double umbrella spray disclosed herein operates satisfactorily at a pressure as low as 15 lbs. as well as at the higher pressures. This makes it possible to control the rate of oil feed by varying the pressure at which the oil is delivered to the nozzle making it unnecessary to provide adjustable parts in connection with the nozzle to vary the effective area of the discharge orifice. This simplifies the construction of the nozzle and greatly lessens the liability of the nozzle to get out of order during operation.

In Figs. 12 to 16 inclusive I have shown a modified form of nozzle in which means are provided for varying the effective area of both the inner and outer annular orifices. Under certain conditions, such as where an unusually large variation in the rate of oil flow is desired or where extremely exact regulation is required, regulation of the discharge orifices may be desirable. In this modification the outer casing 33 has its upper end screwed into a T coupling 34 the stem 35 of which is threaded to receive the oil supply pipe. Upon the lower end of the casing 33 is screwed a casting 36 similar in all respects to the casting 12 shown in Fig. 1. Between the internal shoulder 37 of the casting 36 and the lower end of the casing 33 is clamped an annular washer 38 having slanting passages 39 formed by grooving the inner surface thereof. Slidably fitting within the washer 38 is an inner nozzle head 40 having inner and outer conical surfaces at its lower end similar to the inner and outer surfaces 23 and 25 of the inner head 13 shown in Fig. 1. The head 40 is provided at its upper

end with internal screw threads to receive a sleeve 41. The sleeve 41 has upper and lower apertures 42 and 43 therein to permit free passage of oil thereto. The upper 5 end of the sleeve 41 passes through and has threaded engagement with a plug 44 screwed into the upper end of the T coupling 34. Above the plug 34 the sleeve 41 has a cap 45 screwed thereon and locked against 10 rotation with respect thereto by a pin 46. The cap 45 carries a hand wheel 47 by means of which the sleeve 41 can be rotated for vertical adjustment to vary the area of the outer annular discharge orifice between the 15 casting 36 and head 40. Between an internal shoulder 48 inside the head 40 and the lower end of the sleeve 41 is clamped to a washer 49 having slanting passages 50 therethrough. Slidably fitting within the 20 washer 49 is a pin 51 having a conical point 52 at its lower end. The upper end of the pin 51 has threaded engagement with the cap 45 and carries a hand wheel 53 at its upper end by means of which the pin 51 25 may be adjusted vertically to vary the effective area of the inner discharge orifice. The operation of the adjustable nozzle shown in Figs. 12 to 16 is similar to that of the modification previously described.

30 What I claim is:

1. A spray nozzle comprising a body portion having an outer converging wall terminating in an outwardly flaring wall of considerable depth, a second wall spaced 35 inwardly from the outer wall and lying substantially parallel thereto and terminating at its outer end substantially in the plane of juncture of said converging outer wall and the outwardly flaring wall, a centrally disposed conical portion arranged in spaced relation to and within the second wall and terminating in spaced relation to the outer end thereof said second wall having an outward-

ly flaring outer extremity beyond the conical portion, said outer and second walls and the latter and said conical portion providing concentric and converging passages terminating in inwardly stepped and flaring orifices for first concentrating and subsequently intermingling the separate fluid bodies passing through the nozzle and means for causing said separate fluid bodies to whirl spirally and in opposite directions from said orifices whereby said oppositely whirling annular films may come into contact with each other at a distance from the outer end of the nozzle and break up into a rain spray for complete diffusion of the fluid.

2. A spray nozzle comprising outer, inner and intermediate portions spaced apart and providing concentric passages therebetween, said portions having opposed, spaced and parallel converging walls defining said passages and adapted to concentrate separate streams of fluid passing through the nozzle, means for causing said separate streams of fluid to whirl in opposite spiral paths in said passages, the outer extremities of said outer and intermediate portions terminating in relatively deep outwardly beveled ends providing independent flaring orifices communicating respectively with said converging passages, and the extremity of the intermediate portion extending at least into the plane of the inner end of the outer flaring orifice to concentrically space apart the spirally and oppositely whirling films projected from the nozzle, said films being adapted for contact and interference with one another at a distance from the outer end of the nozzle for breaking up the oppositely whirling annular films into a rain spray for uniform distribution of the fluid.

Signed by me this 23rd day of Sept., 1921.
PIERRE PLANTINGA.
